Attorney

UNITED STATES PATENT OFFICE

ERNEST J. NOEL, OF IRENTON, OHIO, ASSIGNOR TO LOCOMOTIVE FIREBOX COMPANY, OF CHICAGO, ILLINOIS, A CORPORATION OF DELAWARE

LOCOMOTIVE BOILER

Application filed September 16, 1929. Serial No. 392,978.

This invention relates to improvements in locomotive boilers and it consists of the matters hereinafter described and more particularly pointed out in the appended claim.

5 The primary object of the invention is to provide in a boiler of this kind having a firebox of the combustion chamber type, a structure whereby one or more water steaming and circulating elements may be advantageously employed and so disposed in the firebox that the inlet ends may be caused to draw water from the front throat and discharge it through the crown sheet to increase the water steaming and circulating efficiency of the 10 boiler as a whole.

Another object of the invention is to provide in a boiler having a firebox of this kind, an upright transverse water wall spaced rearwardly from the flue sheet and preferably 20 disposed in the plane of the front water leg, whereby thermic siphons may be disposed in the firebox fore and aft said wall and to which the inlet ends of the siphons are operatively connected.

25 Still another object of the invention is to provide a dished portion in that sheet of the transverse water wall opposite the diaphragm in the other sheet and to which the inlet end of an associated siphon is attached 30 whereby the normal width of the water wall is maintained at this point so that the inlet end of the siphon is in no manner restricted by use of the diaphragm.

These objects of the invention as well as 35 others together with the many advantages thereof will more fully appear as I proceed with my specification.

In the drawings:—

Fig. 1 is a longitudinal vertical sectional view through a locomotive boiler embodying my invention.

Fig. 2 is a transverse vertical sectional view through the same on an enlarged scale as taken on the line 2—2 of Fig. 1.

45 Referring now in detail to the locomotive firebox illustrated in the accompanying drawings, the same includes a fire chamber which extends from the back sheet 1 to the flue sheet 2 and from one to the other of the side sheets 3—3. In the open bottom portion of

the fire chamber is located the usual grate as indicated by the dotted line 4. This grate extends from the back sheet 1 to the inner throat sheet 5 which is spaced rearwardly from the flue sheet.

55 The top of the firebox is formed by a crown sheet 6 which extends from the back sheet to the flue sheet and between said flue sheet and inner throat sheet is formed a combustion chamber 7. The top of this combustion chamber is formed by a portion of the crown sheet, its sides 8 are formed by end parts of continuations of the side sheets 3 and its bottom is formed by a horizontal wall 9 that merges into said end parts or continuations of the side 60 sheets as best shown in Fig. 2. In this instance the bottom wall of the combustion chamber extends from the flue sheet to a point spaced forwardly from the plane of the inner throat sheet.

70 The firebox just described is enclosed by a top sheet 10 and outer side sheets 11—11, an outside throat sheet 12 and an outside back plate 13 which provide the wrapper for said firebox and connected to said top sheet, outer 75 side sheets and the outside throat sheet is the boiler shell 14. The several sheets just above mentioned, together with the various sheets of the firebox define the several water legs of the boiler; namely, the front leg or throat 15, the side legs 16—16 and back water legs 17 all closed at the bottom by a mud ring 18. The several coacting sheets are connected together by means of the stay bolts 19.

80 In the inner and outer back sheets are coacting flanges to provide the fuel door opening 20 and connected to the flue sheet within the shell 14 are the flues 21 through which the products of combustion pass from the fire chamber to the smoke box in the manner well known.

85 In the plane of the front water leg 16 I provide an upright transverse water wall 22 which opens at each side into the front ends of the side water legs 16. To form such a 90 water wall the front throat sheet 5 is continued upwardly to form the rear sheet 23 of said wall and in connection therewith is a second sheet 24 spaced forwardly therefrom, that is connected along its bottom edge with 100

the sheet 9 of the combustion chamber. Both sheets are connected together by a rounded top portion 25 and both sheets include end flanges 26 that are welded in corresponding 5 openings in the side sheet 3 and the continuations thereof which form the sides of the combustion chamber. The water wall increases in height at its ends from its mid portion and is in communication at its bottom 10 with both the front water leg 15 and the boiler water space beneath the combustion chamber as best shown in Fig. 1.

In connection with the structure described 15 I may employ one or more sets of water steaming and circulating elements, arranged either fore or aft the water wall or both fore and aft the same and this last mentioned arrangement is shown in Fig. 1.

The water steaming and circulating elements 20 employed herein constitute what have now become known as the Nicholson thermic siphons and when a plurality of such siphons are employed in both the fire and combustion chambers, those in the combustion chambers 25 are disposed in planes between those in the fire chamber. Such elements may be of the shape or form desired but they all embody the same basic parts; namely, a flat, substantially triangular, hollow body that opens 30 through the crown sheet and a tubular neck inclined downwardly therefrom and opening into the transverse water wall 22.

The siphons in the fire chamber are each indicated as a whole by the numeral 27 and 35 the siphons in the combustion chamber are each indicated as a whole by the numeral 28. In each instance, the siphons each include a substantially triangularly shaped flat hollow body 29 suitably stay bolted, and a 40 tubular neck 30.

Each body 29 is open at its top and is flanged for welding in a longitudinally extending slot in the crown sheet in the usual manner.

45 The neck 30 of each siphon 27 in the fire chamber is engaged and welded in a flexible diaphragm 31 formed in the throat sheet 5 in approximately the plane of the bottom of the combustion chamber while the neck 30 50 of each siphon 28 in the combustion chamber is engaged in a flexible diaphragm 32 formed in the front sheet 24 of the water wall in a plane above that of the diaphragms 31. In the rear sheet of the transverse water wall, 55 in line with the diaphragms, are outwardly convexed or dished portions 33 whereby, even though the diaphragms extend into said wall the width thereof in the plane of the inlet necks of the siphons is in no manner reduced 60 or restricted. The opposed sheets of the water wall are suitably stayed to resist internal pressures.

The construction above mentioned permits 35 of the introduction into the firebox of the boiler of a greater number of water steam-

ing and circulating elements than has heretofore been possible whereby the water steaming and circulating efficiency of the boiler is proportionally increased. Again with such elements or siphons disposed in the combustion chamber, assurance is had that the front and higher end of the crown sheet will be flooded with water even though the normal water level falls below the plane of said end of the crown sheet. It is also pointed out 70 that the fore and aft circulation of boiler water is increased by reason of drawing the water from the transverse water wall and discharging it above the crown sheet and again it is pointed out that the transverse water wall permits the locating of the inlet neck 30 of the siphons 27 in a position above the fuel bed burning upon the grate 4.

While in describing my invention, I have referred in detail to the form, arrangement 85 and construction of the various parts thereof, the same is to be considered merely as illustrative so that I do not wish to be limited thereto except as may be specifically set forth in the appended claim.

I claim as my invention:

A locomotive boiler embodying therein, a firebox, a transverse water wall therein and communicating at its ends with the side water legs of the boiler, and including spaced 95 sheets, a thermic siphon in said firebox opening at one end through the crown sheet of the firebox and having a tubular neck at the other end and a flexible diaphragm in one of said sheets in which said neck is 100 secured, the other sheet having an outwardly dished portion in line with said diaphragm.

In testimony whereof, I have hereunto set my hand this 9th day of Sept., 1929.

E. J. NOEL.
